United States Patent and Trademark Office, "U.S. Appl. No. 14/986,068", filed Dec. 31, 2015, 70 Pages.

Primary Examiner — Caron D Veynar

Assistant Examiner — Mehri Bajoul

(74) Attorney, Agent, or Firm — Dorsey & Whitney LLP

(57) **CLAIM**

The ornamental design for the handle, as shown and described.

DESCRIPTION

FIG. 1 shows an isometric view of a handle of an exercise machine.

FIG. 2 shows another isometric view of the handle in FIG. 1.

FIG. 3 shows a front view of the handle in FIG. 2, from a user's perspective when using the exercise machine.

FIG. 4 shows a rear view of the handle in FIG. 2.

FIG. 5 shows a right side view of the handle in FIG. 2.

FIG. 6 shows a left side view of the handle in FIG. 2.

FIG. 7 shows a top view of the handle in FIG. 2; and,

FIG. 8 shows a bottom view of the handle in FIG. 2.

The broken lines are provided for illustrative purposes only, and form no part of the claimed design.

1 Claim, 6 Drawing Sheets
